CARLOS B. DREW, OF BOSTON, MASSACHUSETTS, ASSIGNOR TO UNDERHILL
EDGE-TOOL COMPANY, OF NASHUA, NEW HAMPSHIRE.

Design No. 4,029, dated May 17, 1870.

DESIGN FOR AN AX.

The Schedule referred to in these Letters Patent and making part of the same.

To all persons to whom these presents may come:

Be it known that I, CARLOS B. DREW, of Boston, of the county of Suffolk and State of Massachusetts, have invented or produced a new and useful Design for an Ax; and do hereby declare the same to be fully described as follows, and to be represented in the accompanying drawings, of which—

Figure 1 is a side view;

Figures 2 and 3 opposite edge views; and

Figure 4, a view of the cutting-end of an ax formed in accordance with my design, the form causing, in practice, a chip, on being cut from a tree or log, to split at or about at its middle, into two pieces.

In carrying out the design I form the ax on each of its sides with an angular ridge, $a b e$, at its middle, with plane slopes in opposite directions from such ridge down to the cutting-edge $c e d$, such slopes being bounded by the oblique lines $a c$ and $a d$, which ex-

tend from a point, a , even, or about so, with the front edge or part of the ax-eye A.

From the lines $a c$, $a d$, the blade of the ax is curved down to the eye part, in manner as represented, the said eye portion, as well as the cutting-edge, being shaped as represented, the said cutting-edge having an elliptical or oval formation.

By my form of an ax the cutting-part is practically composed of two triangular pyramids, $d a e a$, and $c a e a$, or wedges projected in opposite directions from a common triangular base, $a e a$.

I claim as my invention—

The ax design as represented and hereinbefore described.

CARLOS B. DREW.
